COMBINED GAME BOARD AND SUITCASE-TYPE CONTAINER

John W. Ryan, Bel Air, and Cecil Frederick Adickes, Jr.,
Woodland Hills, Calif., assignors to Mattel, Inc., a corporation of California

Filed Feb. 1, 1966, Ser. No. 880

Term of patent 14 years

(Cl. D34—5)

FIG. 1

FIG. 4

FIG. 5

FIG. 2

FIG. 3

FIG. 1 is a plan view of a combined game board and suitcase-type container, showing our new design in an open, game-playing position;

FIG. 2 is a perspective view of the design in a partially-open, game-playing position;

FIG. 3 is a side elevational view of the design in a closed, storage position, the opposite side being identical;

FIG. 4 is an end elevational view taken from the left as seen in FIG. 3; and

FIG. 5 is a top plan view of FIG. 3.

The dominant features of our design are shown in solid lines.

We claim:

The ornamental design for a combined game board and suitcase-type container, as shown and described.
